UNITED STATES PATENT OFFICE.

THOMAS CURRAN, OF CHILlicothe, ILLINOIS.

AUTOMATIC VALVE CONTROL.

1,387,130.

Specification of Letters Patent. Patented Aug. 9, 1921.

Application filed November 13, 1919. Serial No. 337,881.

To all whom it may concern:

Be it known that I, THOMAS CURRAN, a citizen of the United States, and a resident of Chillicothe, in the county of Peoria and 5 State of Illinois, have invented a new and useful Improvement in Automatic Valve Control, of which the following is a full, clear, and exact description.

My invention relates to improvements in 10 automatic valve control mechanisms, and it consists in the combinations, constructions and arrangements herein described and claimed.

An object of my invention is to provide a 15 device by means of which a valve, such as that leading from a sludge treating tank, may be operated automatically and periodically without any attention, for the draining of the treating tank.

20 A further object of my invention is to provide a device of the type described, which is operated by hydraulic means, thereby insuring the positive opening and closing of the valve.

25 A further object of my invention is to provide an automatic valve controlling mechanism, which may be easily regulated to open or close the valve at any predetermined time.

30 Other objects and advantages will appear in the following specification, and the novel features of the invention will be particularly pointed out in the appended claims.

My invention is illustrated in the accompanying drawings, forming part of this application, in which—

Figure 1 is a side view of the valve-operating mechanism, showing the position when the valve is open.

40 Fig. 2 is a similar view showing the position when the valve is opened, and

Fig. 3 is a detail view of a drain valve.

The invention may be applied for the purpose of controlling valves used in any industry where an automatic control is desirable. In the drawings I have shown a treating tank 1, such as that employed for softening water, which is to be used by locomotives or boilers of steam engines. The main purpose 45 of the present invention is to provide a device for automatically opening a valve to draw off the sludge from the treating tank. To this end, an outlet pipe 2 is connected with the tank 1 and is provided with a gate-valve 3, having an outlet 4 leading to any suitable place for depositing the sludge.

Mounted above the gate-valve is a cylinder 5, this cylinder being supported in any suitable manner, as by uprights 6. Within the cylinder is a piston 7 whose stem 8 is connected with the gate-valve. A feed pipe 9 communicates with a three-way valve 10 at one end. The outlet pipe 12 has a branch 13 communicating with the three-way valve 10.

Disposed above the cylinder 5 is a lever 15, which is fulcrumed at 16. One end of the lever is provided with a weight 17. A pivoted arm 18 connects with an arm 19 for operating the three-way valve 10, and also with an arm 20 for operating the three-way 65 valve 11.

At 21 I have shown a bucket which is open at its top and which is suspended from the end of the lever 15 by means of a link 22. The bucket is designed to be moved vertically in guides 23. The lower end of the bucket has an outlet pipe 24, provided with a valve 25 at the lower end. At 26 I have shown a stationary post or pin which is arranged to engage the valve when the bucket 70 moves downwardly. A valve 27 is provided for regulating the flow of water from the bucket.

In order to provide for a sudden movement of the bucket downwardly or upwardly, 85 I provide a spring-pressed engaging member 28, having a recess arranged to receive triangular shaped lugs 29 carried by the bucket.

From the foregoing description of the various parts of the device, the operation thereof may be readily understood. The control valve 30 in the feed pipe 9 is opened so as to permit a flow of water under pressure from any suitable source to the cylinder 5. 90 In Fig. 2 the three-way valve 10 is turned so as to admit water from the pipe 9 into the upper end of the cylinder 5, thus forcing the piston 7 downwardly and holding the gate valve 3 shut. At 31 I have shown a feed pipe for conveying water from any suitable source. A regulating valve 32 in this feed pipe 31 controls the flow of water out of the feed pipe into the bucket 21. This may be made as fast or as slow as desirable, merely 100 by turning the valve to the proper position. The water is allowed to drip or flow into the bucket continuously. Now when the latter has been filled to a predetermined height, the weight of the water will overbalance 105 the weights 17, and also the resistance caused by the spring-pressed member 28, and the 110

bucket will suddenly move downwardly. The downward movement of the bucket will cause the arms 19 and 20 to swing upwardly, cutting off the flow of water from the feed 5 pipe 9 to the upper part of the cylinder and establishing communication between the pipe 9 and the lower part of the cylinder. At the same time, the overflow pipe 12 will have communication established through the 10 pipe 13 and the three-way valve 10, the pipe 14 being closed by the valve 11. The plunger will now be moved upwardly, thereby opening the gate valve. When the check valve 25 engages the pin 26, the latter will 15 open the valve and permit the water in the bucket 21 to run out. The time which it takes this water to run out may be regulated by means of the valve 27. Owing to the fact that the lug 29 is held by the spring- 20 pressed engaging member 28, the bucket is held from moving upwardly until enough water has run out, so that the weight 17 overbalances the bucket, whereupon the latter will be suddenly moved upwardly, thus 25 causing the shifting of the three-way valves 10 and 11, and the reversal of the movement of the piston so as to close the valves.

Since the cylinder 5 is fed by water under pressure, the gate-valve is positively moved, 30 both to close the valve and also to open it.

While I have shown the water supplied to the bucket 21 as being taken from an independent source, it is obvious that it might be taken from any source, such as that which 35 supplies the cylinder 5.

The device is simple in construction, positive in action, and is not liable to easily get out of order.

I claim:

40 1. The combination of a discharge pipe, a control valve therefor, a cylinder, a piston in said cylinder connected with the control valve, a three-way valve at each end of the cylinder, an inlet and outlet pipe connected 45 with said three-way valves, a weighted lever connected with said three-way valves, a movable bucket connected with said lever,

means for filling said bucket with liquid, and means for regulating the flow of the liquid into the bucket.

50 2. The combination of a discharge pipe, a control valve therefor, a cylinder, a piston in said cylinder connected with the control valve, a three-way valve at each end of the cylinder, an inlet and outlet pipe connected 55 with said three-way valves, a weighted lever connected with said three-way valves, a movable bucket connected with said lever, means for filling said bucket with liquid, means for regulating the flow of the liquid into the 60 bucket, and spring means for resisting the movement of the bucket in either direction.

65 3. The combination of a discharge pipe, a control valve therefor, a cylinder, a piston in said cylinder connected with the control 65 valve, a three-way valve at each end of the cylinder, an inlet and outlet pipe connected with said three-way valves, a weighted lever connected with said three-way valves, a movable bucket connected with said lever, means 70 for filling said bucket with liquid, means for regulating the flow of the liquid into the bucket, a valve for draining the contents of the bucket, spring means for resisting the movement of the bucket in either direction, 75 and a stationary engaging member for opening said last named valve.

80 4. The combination of a discharge pipe, a control valve therefor, a cylinder, a piston in said cylinder connected with the control valve, a three-way valve at each end of the cylinder, an inlet and outlet pipe connected 85 with said three-way valves, a weighted lever connected with said three-way valves, a movable bucket connected with said lever, means for filling said bucket with liquid, means for regulating the flow of the liquid into the bucket, spring means for resisting the movement of the bucket in either direction, a valve for draining the contents of the bucket, 90 a stationary engaging member for opening said valve, and means for regulating the flow of fluid through said valve.

THOMAS CURRAN.
